UNITED STATES PATENT OFFICE

2,516,636

BAND CLEANING MECHANISM FOR CONTINUOUS VULCANIZING MACHINES

Grosvenor D. Marcy, Newton Highlands, Mass., assignor to Boston Woven Hose & Rubber Company, Cambridge, Mass., a corporation of Massachusetts

Application March 4, 1947, Serial No. 732,255

9 Claims. (Cl. 18—6)

1

My invention relates to machinery for carrying out the continuous vulcanizing, molding or pressing of sheet stock such, for example, as rubberized belting, rubber flooring, thermoplastic materials, or combinations of textile and plastic compositions. Machines of the type to which the invention relates employ a heated drum on which bears a flexible steel pressure band, the arrangement being such that the material is fed between the surfaces of the drum and the pressure band and removed therefrom after having passed over a large portion of the circumference of the drum. Such machines are discussed in detail in United States Letters Patent No. 2,039,271 issued to John M. Bierer on April 28, 1936.

One important factor in the process carried out on machinery of this type is the character of the surface imparted to the stock by the operation of the machine. It has been found that the surface of the band which presses against the material rapidly becomes dull and foul with traces of the material against which the band has been pressed. In consequence the surface effect imparted to the material reflects the condition of the band surface and is also dull, characterless and streaked. A particularly difficult problem has been encountered when the machine is used first upon material of one color and then upon material of a different color. The scraps or traces of the first material stick to the band surface and come off to some extent on the second material to form streaks and spots which so mar the appearance of the material as to reduce its sales appeal.

The most important object of my invention is to provide apparatus by means of which the operating surface of the pressure band can be continuously scoured and cleaned while the machine is in operation and so that a freshly scoured surface is always presented to incoming material.

The most important feature of my invention resides in the combination of a motor-driven brush and means for automatically reciprocating the revolving brush across the surface of the band at a sufficient rate of speed to insure that no portion of the band escapes the scouring action from the brush.

These and other objects and features of my invention will be more readily understood and appreciated from the following detailed description of a preferred embodiment thereof selected for purposes of illustration and shown in the accompanying drawing, in which:

Fig. 1 is a view in longitudinal cross section

through the entire apparatus, including a view in end elevation of the cleaning apparatus,

Fig. 2 is a view in end elevation of the cleaning apparatus showing it detached from the machine,

Fig. 3 is a view in cross section along the line 3—3 of Fig. 2,

Fig. 4 is a view, on a larger scale, showing the cleaning apparatus in end elevation secured in operating position on the machine,

10 Fig. 5 is a view partly in cross section and partly in plan showing the machine in its operating position,

Fig. 6 is a view in end elevation of a portion of the cleaning apparatus taken along the line 15 6—6 of Fig. 5, and

Fig. 7 is a view in cross section through the guide and clamp.

The machine illustrated in the drawing is representative of what may be referred to for convenience as continuous rotary vulcanizing machinery and is organized about a pair of substantially identical skeleton side frames 10 of suitably heavy steel webbing. Mounted transversely within the frames 10 and journaled for rotation

20 is a large diameter hollow steel cylinder or drum 12 carried on a shaft 14 and disposed adjacent an upper roller 16 and a lower roller 18, both smaller in diameter than the drum 12 and mounted for rotation on axes parallel to the shaft 14. A third roller 20 is mounted in the rear of the frame upon a shaft 22 journaled in bearings provided with hydraulic pressure cylinders 24 so that the distance between the shaft 14 and the shaft 22 may be varied. An endless flexible steel

25 pressure band 26 is looped over the drum 12 and about the rollers 16, 18 and 20 as shown clearly in Fig. 1 so that the band embraces a considerable portion of the circumference of the drum 12. The material 28 which is to be vulcanized, molded, or pressed in the machine is led from a reel (not shown) to the bite of the pressure band 26 and the drum 12.

30 The rollers and drum are rotated by means not shown, and the drum 12 and the band 26 are usually heated by steam jackets or other means (not shown). The material 28 travels about the surface of the drum 12, leaving it adjacent the upper roller 16; then the material 28 follows on the surface of the band 26 over the roller 16 and between the frames of the machine

35 from whence it is rolled up by any suitable mechanism (not shown). The hydraulic cylinders 24 are manipulated until the band is pressed against the material 28 with the desired degree of pressure.

Secured to the side frames 10 and in align-

ment with each other are two steel plates 30 providing anchorage for the ends of a stout steel tube 32 which extends transversely between the frames. Each end of the tube 32 is filled with a block 34 carrying a stud 36 passing through a hole in the plate 30 and threaded to receive a nut 38. The nuts 38 secure the tube 32 rigidly to the plates 30. Above and parallel to the tube 32 is disposed a shaft 40 threaded intermediate its ends as shown at 42 and journalled in bearings 46 mounted in the plate 30. One end of the shaft 40 projects beyond the side frame 10 and carries a pulley 48 for a V-belt 50 driven from a motor 52 which is mounted on a base plate 53 at the side of the machine. The threaded portion 42 of the shaft 40 carries a knurled nut 44.

A flat bar 54 spans the frames parallel to the tube 32 and the shaft 40 and is secured at its ends to a pair of plates 55 secured to the frames 10. The bar 54 is located somewhat higher than the tube and shaft, and all three members are disposed beneath the bottom stretch of the band 26 adjacent the rear roll 20. Closely adjacent the bar 54 and parallel thereto is a rod 58 mounted for axial movement in three bearings 56 secured to the bar 54. Fixed to the rod intermediate its ends is a pair of spaced collars 128 and 130, while one end of the rod 58 is extended beyond the frame to receive a cam 60 which operates with a roller 62 carried on the end of a switch arm 64, mounted on a bracket 66 arranged to control the direction of the motor 52, and spring-loaded to be urged inwardly toward the frame 10. The rod 58 may be moved axially to throw the switch arm 64 from the full-line position to the position indicated in broken lines in Fig. 5.

The cleaner is organized about a stout flat metal plate 68 from which depend three supporting legs 70 mounted at their lower ends on casters 12 and in effect forming a dolly. A hollow steel housing 74 is suspended from the plate 68 and provides support for a motor 76 carrying a pulley 78 with three sheaves for a V-belt 84 which passes about one of three sheaves of a pulley 82 mounted on the end of a spindle 80 journalled in the housing 74 and projecting upwardly through the plate 68. A flat steel disk 86 is secured to the spindle 80 by means of a nut 87 and is provided with three holes for the reception of stout pins 88 each of which is surrounded by a compression spring 90 bearing against the disk 86 and against a second steel disk 94 in which the upper ends of the pins 88 are anchored. The lower end of each pin 88 is bored to receive a retaining pin 92 which prevents a separation of the pins and disk 94 from the disk 86. Screwed to the upper surface of the disk 94 is the wooden back 96 of a circular wire brush 98, and it will be seen that when the motor 76 is turned on, the brush 98 will be revolved about the axis of the spindle 80 at a rate according to the position of the belt 84 on the sheaves of the pulleys 78 and 82. Mounted on one edge of the plate 68 is a pair of depending stationary jaws 100, spaced from each other and secured to the plate 68 by bolts 101. Each stationary jaw 100 carries a pivot pin 104 about which swings a movable jaw member 102 terminating in its free end in a U-shaped lug 110. The jaws 100 and 102 are curved to fit the contour of the steel tube 32. Pivotally mounted in the edge of the steel plate 68 is a pair of threaded studs 106 each of which carries a threaded cap 108. In mounting the cleaning device upon the machine, the stationary jaws 100 are fitted over the tube 32 and the mov-

able jaws 102 are then swung up to engage the shanks of the studs 106, following which the caps 108 are screwed in until the tube 32 is locked to the plate 68. The clamps are dimensioned to permit the plate 68 to slide back and forth on the steel tube as a guide; that is to say, the jaws do not grip tightly.

A third stationary jaw 112 is secured to the upper side of the plate 68 and carries a pivoting jaw 114 which carries at its free end a U-shaped lug dimensioned to fit the shank of a pivotally mounted stud 116 carried by the edge of the plate 68 and receiving a threaded cap 118. The upper jaw is dimensioned to engage the nut 44 on the shaft 40 and to grip it tightly so that the nut cannot turn with the shaft. The other end of the plate carries a lug 120 to which a dog leg link 122 is pivotally mounted. The link 122 carries at its free end a roller 124 having an up-standing rim or shoulder 126. After the clamps have been engaged on the tube 32, the housing 74 is swung upwardly until the roller 124 slips over the top of the flat bar 54, and the upper clamp 114 is then secured about the nut 44. In this position the wire brush 98 bears against the lower surface of the pressure band 26. The bearings 56 for the cam shaft 58 are so dimensioned that the roller 124 does not encounter them, but the rim 126 will strike against the collars 128 and 130.

In operating the device the motor 52 is started which turns the shaft 40 forcing the nut 44 in one direction or the other. The plate 68 and the housing 74 are carried with the nut, the clamps on the tube 32 fitting loosely enough to permit easy sliding. The roller 124 rolls on the upper surface of the flat bar 54 until the rim 126 encounters one of the collars 128 or 130. At that time the cam shaft 58 is pushed in one direction or the other to change the position of the switch arm 64 and reverse the motor 52. This starts the shaft 40 turning in the opposite direction and the plate and its associated mechanism are carried back in the opposite direction until the rim 126 again operates the cam shaft 58 to reverse the direction of movement. The collars 128 and 130 may be adjusted to vary the length of the cleaning strokes.

When the motor 76 is turned on, the brush 98 revolves at about 300 R. P. M. and scours and polishes the surface of the pressure band 26. It will be understood that the band 26 moves very slowly. I have found it satisfactory to adjust the speed of reciprocation of the brush 98 so that any given point on the surface of the band is scoured three times before it passes through a space equivalent to the diameter of the brush. The scouring is aided by the fact that the band is heated, and the result is a surface polish of high luster. As will be apparent from an inspection of Fig. 1, the pressure surface of the band is scoured after it leaves the drum and before it returns to the drum so that no portion of the stock is acted on by a dirty portion of the band surface. I have found that a wire brush is quite satisfactory, although I may alternatively employ a pad of steel wool, emery cloth, or any other suitable scouring or polishing material. Also I may impregnate a scouring pad with any suitable cleansing solution, detergent, or abrasive.

The disposition of the guide 32 and the bar 54 is such that the plate 68 is substantially parallel to the portion of the band above it. Thus the brush 98 bears evenly on the band. The springs 90, however, provide a yielding support 75 for the brush, permitting the brush to accom-

mediate itself to the surface of the band and thus to compensate for slight changes in the angle of the band due to movement of the tension roll 20 which is always under hydraulic pressure.

It will be apparent that the band-scouring mechanism, when in operative position, is suspended from the tube 32 and the bar 54. The legs 70 and their casters 72 provide convenient means for trundling the cleaner to and from a machine and facilitate the operation of changing the brush or adjusting the speed thereof.

It will thus be seen that I have provided a power driven band-scouring mechanism located in contact with the active face of the pressure band as it approaches the drum, in combination with power-operated means for traversing the scouring mechanism across the pressure band. The scouring tool, moreover, is yieldingly supported for universal adjustment in respect to the band and so operates with a uniform degree of pressure regardless of variations in the angle of the band travel.

The improvement in the quality of the surface of the stock which is occasioned by the use of the cleaning or scouring mechanisms herein described is most important. The stock comes out of machines with a bright lustrous surface, extremely attractive to the eye and the effect not only lends an air of quality to belting and similar products, but also materially increases the salability of such products as flooring. Furthermore a machine equipped with the cleaning mechanism of my invention may be used to operate on stock materials of different colors in rapid succession without any necessity for stopping the machine between runs to clean or prepare the band surface.

The particular mechanism shown in the drawing is one which has proved eminently satisfactory in service, but is only one example of an embodiment of the invention.

Having now disclosed my invention what I claim as new and desire to secure by Letters Patent of the United States is:

1. In a press including a frame and an endless pressure band movable along a predetermined path in the frame; a band cleaner comprising a guide spanning the frame adjacent one portion of the band path, a plate slidably mounted on the guide, a brush-driving mechanism secured to the plate, a brush driven by said mechanism and mounted in position to bear on the band, and a reversible motor-driven mechanism for reciprocating the plate, brush and brush-driving mechanism on said guide within the frame.

2. In a press including a frame and an endless band movable along a predetermined path in the frame; a band cleaner comprising a guide spanning the frame adjacent the band, a threaded shaft journalled in the frame parallel to the guide, a nut threaded on said shaft, a housing, a first clamp mounting said housing to slide on said guide, another clamp securing said housing to said nut, a motor driven spindle journalled in said housing, a brush secured to said spindle in position to bear on said band, a reversible motor arranged to drive the threaded shaft and slide the housing along the guide, a switch controlling the direction of the motor, and means operated by the housing to throw the switch every time the housing approaches one end of the guide.

3. In a press including a frame and an endless pressure band movable along a predetermined path in the frame; a band cleaner comprising a guide spanning the frame adjacent to the path

of the band and at right angles thereto, a motor mounted to slide on the guide, a brush driven by said motor and bearing on the band, and an electro-mechanical train for sliding said motor and brush to and fro on said guide.

4. In a rotary vulcanizing machine including a revolving drum, and an endless pressure band movable over a portion of the periphery of the drum, a band cleaner comprising a guide disposed transversely to one portion of the path of the band, a housing slidably mounted on the guide, a first motor supported by the housing, a spindle driven by the motor, a brush carried by the spindle and disposed to bear on the band, a second motor, a mechanical train driven by the second motor and arranged to slide the housing on the guide, a switch controlling the direction of the second motor, and a cam controlling the switch and actuated by the motion of the housing.

5. In a press including a frame and an endless pressure band movable along a predetermined path in the frame; a band cleaner comprising a guide spanning the frame and disposed transversely to one portion of the path of the band, a bar spanning the frame parallel to the guide, a cam shaft mounted adjacent and parallel to the bar, a housing mounted to slide on the guide and the bar, a rotary scourer mounted in the housing, a motor-driven mechanical train for sliding the housing along the guide and bar, a switch controlling the direction of the motor, a cam secured to the cam shaft and actuating said switch, and means on the housing for operating the cam shaft.

6. In a press including a frame and an endless pressure band movable along a predetermined path in the frame; a band cleaner comprising a bar spanning the frame, a housing, a roller secured to the housing and bearing on the bar, motor-driven means for moving the housing along the bar, a rotary scourer mounted in the housing in position to bear on the band, a switch controlling the direction of the motor, a cam shaft slidably mounted adjacent the bar, a spaced pair of collars adjustably secured to the cam shaft in position to be struck by said roller, and a cam mounted on the cam shaft in position to control said switch.

7. In a machine for vulcanizing or curing a continuous web of sheet stock and including in its structure a heated drum and a metallic pressure band supported on the circumferential surface of the drum and guided thereto from beneath, and a guide roll about which the band passes and reverses its direction of movement in approaching the drum; power driven band-scouring mechanism located in contact with the drum-engaging surface of the pressure band as it approaches said guide roll, said mechanism including a scouring tool having a yielding and self-adjusting mounting permitting the tool to accommodate itself to angular variations in the position of the pressure band, spaced members supporting said mechanism for straight line movement transversely of the band, and power operated means for bodily reciprocating the scouring mechanism on said members.

8. In a press including a frame and an endless pressure band movable along a predetermined path in the frame; two supporting members spanning the frame adjacent to the band, one supporting member consisting of a tube and the other consisting of a bar, band cleaning mechanism including a power driven brush suspended beneath the band upon said supporting members,

a clamp mounted on the mechanism and fitting loosely around the tube, said clamp being detachable from the tube, a link pivotally mounted on the mechanism, and a roller carried by the link and traveling upon the bar.

9. In a press including a frame and an endless pressure band movable along a predetermined path in the frame; band cleaning mechanism suspended below the band and including a rotating brush bearing on the lower surface of the band, the brush consisting of a disk, bristles mounted in the disk, a plurality of pins anchored in the disk on the side opposite the bristles, a second disk having holes through which the pins extend, springs surrounding the pins in the space 15 between the two disks, means for preventing the pins from becoming separated from the second

disk, and a driven shaft operatively connected to the second disk.
